MAGNETIC KNIFE AND TOOL HOLDER

Albert S. Schmitman, Cleveland, and Marvin Schmitman, Cleveland Heights, Ohio

Application September 29, 1949, Serial No. 5,212

Term of patent 3½ years

(Cl. D44—29)

To all whom it may concern:

Be it known that we, Albert S. Schmitman and Marvin Schmitman, citizens of the United States, residing in the city of Cleveland, county of Cuyahoga, and State of Ohio, and city of Cleveland Heights, county of Cuyahoga, and State of Ohio, respectively, have invented a new, original, and ornamental Design for a Magnetic Knife and Tool Holder, of which the following is a specification, reference being had to the accompanying drawing, forming a part thereof.

Figure 1 is a front elevation of a magnetic knife and tool holder, showing our new design; Figure 2 is a top view of the same; and Figure 3 is an end view of the same.

We claim:

The ornamental design for a magnetic knife and tool holder, substantially as shown and described.

ALBERT S. SCHMITMAN.
MARVIN SCHMITMAN.
